UNITED STATES PATENT OFFICE.

FRANCIS H. RICHARDS, OF HARTFORD, CONNECTICUT, ASSIGNOR, BY MESNE ASSIGNMENTS,
TO AMERICAN TYPOGRAPHIC CORPORATION, A CORPORATION OF NEW JERSEY.

TYPE-BAR MACHINE.

No. 919,229.

Specification of Letters Patent.

Patented April 20, 1909.

Application filed April 16, 1901, Serial No. 56,164. Renewed August 13, 1908. Serial No. 448,377.

To all whom it may concern:

Be it known that I, FRANCIS H. RICHARDS, a citizen of the United States, residing at Hartford, in the county of Hartford and 5 State of Connecticut, have invented certain new and useful Improvements in Type-Bar Machines, of which the following is a specification.

My present invention relates to mechanisms and to organizations thereof, each of the mechanisms being capable of performing a particular operation relating to the process of forming typebars from a continuous ribbon or strip of type-formable material, while 10 the organization of said mechanisms according to my present invention provides for the performance of such operations in a proper sequential order. Such an organization of mechanisms ordinarily includes 15 members adapted to swage or forge types upon the edge of such ribbon or strip, to trim the continuous typebar so formed and to divide the same into lengths to form typebars, besides embodying various features of 20 construction and combinations of parts all of which, individually and as organized in an operative machine specified as above, are described in the following specification with the aid of the accompanying drawings.

30 In these drawings, Figure 1 is a front elevation of such a typebar-machine embodying my improvements, certain parts being broken away. Fig. 2 is a longitudinal vertical section thereof, the plane of this section 35 being somewhat removed from that of the axis of the main driving-shaft of the machine as shown in Fig. 1, although this shaft and certain parts, some of which are mounted thereon, are shown at full in this figure 40 while certain other parts are omitted entirely, or broken away. Fig. 3 is a view of the machine as seen from the rear, certain parts being also broken away. Fig. 4 is a view looking at the underside of the machine, 45 certain parts in this figure being likewise broken away. Fig. 5 is a plan view of the machine upon a somewhat smaller scale than that to which the preceding and succeeding views are drawn. Fig. 6 is likewise a plan 50 view, certain parts being omitted, while certain other parts are shown in section. Fig. 7 is a view similar to Fig. 6, with the die-head and certain portions of the die-adjusting mechanism, shown in the latter figure, 55 omitted. Fig. 8 is an elevational view of

the machine as seen from one end, certain parts being broken away. Fig. 9 is an elevational view of the machine as seen from the opposite end. Fig. 10 is a transverse vertical section on the plane of the broken line 10—10 in Fig. 6, looking in the direction of the arrow adjacent to that line, certain of the parts being broken away, while certain other parts are wholly omitted. Fig. 11 is a similar transverse section upon the plane, however, of the line 11—11 in Fig. 1, looking in the direction of the arrow adjacent to that line, certain portions being shown in elevation, while certain other portions are broken away. Figs. 12, 13, 14 and 15 are plan views representing various positions assumed by certain indicator mechanism designed for the purpose of indicating to the operator when an amount of feed movement of the strip has taken place nearly sufficient to 75 form a typebar length. Fig. 16 is a sectional elevation illustrating certain feed mechanism for effecting a step-by-step or intermittent motion of the continuous typebar-blank. Fig. 17 is a perspective view representing a 80 carrier for moving the work-holder for the strip or ribbon toward and away from the dies during the formation of successive types and spaces. Fig. 18 is a perspective view of such work-holder with one of its guide members. Fig. 19 is a similar view of one of such members. Fig. 20 is also a perspective view showing a support for the journal portion of one of such members. Fig. 21 is a perspective view of a cutting instrument for removing 85 surplus material from the continuous strip after such material has been forced beyond the planes of the sides of the strip as the result of operating upon the latter to form types upon its edge. Fig. 22 is an elevation of certain indicator mechanism showing the relation of said mechanism to the strip or ribbon. Fig. 23 is a perspective view of a portion of the mechanism shown in Fig. 22 and a portion of the strip or 90 ribbon with which it engages. Fig. 24 is an elevation of a locking-plate and shows the relation of certain die-bars and the die-bar head thereto. Fig. 25 is a side view of such locking-plate and a portion of other parts 100 indicated in Fig. 24. Fig. 26 is a view similar to Fig. 25, but shows certain parts in section, the plane of which is the line 26—26 in Fig. 24. Fig. 27 is an elevation of a die-bar and a portion of the die-bar shifter. Fig. 28 105

is a cross section of the die-bar. Fig. 29 is a plan view thereof showing the dies thereon and a certain feed element or plate at the side of the dies. Fig. 30 is an elevation similar to Fig. 27 but shows a die-bar construction involving an additional feature, the purpose of which will appear later. Fig. 31 is an elevation on a somewhat smaller scale of a portion of a die-bar showing in what manner 5 a certain locking-plate indicated in section 10 engages with each die-bar. Fig. 32 is a view of the type faces of a number of assembled typebars and represents the maximum and minimum limits of length within which the 15 strip or ribbon is severed in the present machine to form typebars. Fig. 33 is a perspective view of a cam-shaft and shows the operative connection therewith of a key for 20 releasing the shaft and permitting it to be rotated.

Similar characters of reference designate 25 corresponding parts in all the figures of the drawings.

The machine set forth in the drawings attached to the present specification is adapted 30 to receive a blank in the form of a continuous strip or ribbon supplied to it from a coil of the same, for the sake of convenience, to form on the edge thereof a succession of composed types suitable for typographic purposes and to remove from the stock of the blank excess material that may have been forced beyond the sides thereof in consequence 35 of operating upon its edge to form types and type-separating spaces.

The framework of the machine comprises in a general way a main frame or bed and various accessories and framework details or elements carried thereon or thereby. The 40 main frame as shown herein comprises a bed-plate of suitable form and construction to support the various operative parts of the machine, and is designated in a general way by B. This bed-plate B may be supported 45 by suitable legs b as shown. The type-forming dies may be selected and brought successively to the type-forming point in any appropriate manner and by any suitable mechanism. For the purpose of illustration, 50 however, in the present machine the various dies for forming individual types are designed to be brought to the type-forming point manually—that is to say, the dies are hand adjustable from a position in which 55 they are incapable of forming types into a position in which they are severally capable of so operating. To admit of this adjustability the dies may conveniently be carried by a head or carrier designated in a general 60 way by C, which, as here constructed, is movable about an axis defined by a shaft 2 extending from opposite ends of the head (see particularly Fig. 2) and journaled in 65 bearings formed in or supported by an upright 3 adjacent to one end of the head and

an upright 4 adjacent to the opposite end thereof. These several uprights extend upward from the bed-plate B, and it will be noticed in the present construction that the bearing afforded by the upright 4 for the shaft 2 is in bearing portions at the extremities of the end arms 4^a and 4^b of the upright, and that these bearing portions do not together extend the whole length of the upright; hence a space is provided between them within which there is attached a fixture to the shaft referred to at length hereinafter. 70

The mounting of the head C is shown and has been described to be such as to enable the same to be angularly adjusted and such adjustability permits, in the present construction, any one of a number of lines of dies extending axially of the head to be brought into juxtaposition to or in line with the point where a die is to operate upon the edge of the blank to form a type and for the purpose of temporarily locking the head in its angularly adjusted position a locking device is preferably provided consisting in this instance of a spring finger 5 secured to the bed-plate B, (see, for instance, Fig. 10,) whose upper angular or detent portion 5^a is adapted to enter any one of a number of notches 5^b formed in a plate 5² affixed to the head C. The resiliency of the finger 5 causes its detent portion 5^a to spring into a notch when the same is brought opposite such portion, thereby retaining the head in position, although permitting of the detent to be withdrawn from the notch when a sufficient force is applied to the head through the medium of any suitable manually-operated device, herein shown as a handle, designated in a general way by C^a, to turn the head to another rotatorial position. 85

As constructed and organized in the present case and as set forth in the drawings there is provision not only for an angular adjustment for the purpose of bringing different dies into operative relation with the blank, but for an adjustment longitudinally of the head as well, whereby the capacity of the machine is increased over that which would exist if the former adjustability alone were present. This latter—that is, end-wise—adjustment is rendered effective for the purpose set forth by supporting or forming a number of dies each being designated in a general way by d upon a die-bar D, a number of which latter are mounted in suitable recesses c in the head C corresponding to and so related to the described notches 5^b that a bar is in line with the type-forming point when the detent portion 5^a of the locking finger 5 has entered a notch. The several bars D may be slidably fitted in any appropriate manner to their respective recesses, the present construction embodying a longitudinal tongue or rib d² which extends inwardly into the guide space and is fitted to 100 105 110 115 120 125 130

a corresponding channel in the face of the bar.

The dies *d* may be of any suitable character and provided with accessory parts or units 5 provided therewith, dependent upon the nature of the action which it is designed shall take place during the process of type formation. According to the present construction and mode of operation and as embodied in 10 the present invention, the blank upon which types are formed is fed across the type-forming point and a type is produced by a forging operation which causes the forcing or squeezing of excess material outward laterally of 15 the blank while the die is operating upon a preferably confined portion of the edge of the latter. The confining of the field of action of the die for the purpose of controlling the movement of the excess material and directing 20 it sidewise of the bar and for effectively protecting an adjacent formed type may be brought about by the employment of retaining walls at the side or sides of the die, endwise of the blank, these walls taking the form 25 in the present machine of longitudinal flanges *b*², *b*³ on the edges of each bar *D*. The flange which is located forwardly of the forming type when a die is positioned to compress the 30 blank, is here shown as of sufficient width to form a space extending into the character field of the next succeeding type to be formed. Furthermore, one of the flanges at the edge of the bar is also shown provided with an opening indicated in a general way 35 by *C*⁴ opposite each die through which flowage can take place in the direction of and against the base of the contiguous type-block.

As organized in the present instance a bar 40 *D* is in an adjusted position, so far as the angular movement of the head *C* is concerned when the latter has been turned upon its axis to bring the bar to the lowest point of the arc in which the latter moves, as a result of 45 the rotarial movement of the head. In this position the bar is adapted to be shifted lengthwise in its guides to bring any particular die *d* upon the bar over the blank by means of a shifter designated in a general 50 way by *E*. This shifter *E* comprises in the form thereof shown a shifter bar *6* fitted to slide in suitable openings in the direction of the lengthwise movement of which the several bars *D* when rotarily adjusted are capable. These openings through which the shifter bar *6* moves are here shown to be formed in plates *6*^a, *6*^a secured to the arms 55 *4*^a, *4*^b of the upright *4* in such a position as will bring the shifter bar in line with a die-bar *D* when this latter is located in line with the type-forming point as pointed out above, in which position the die-bar may be adjusted in its guides by means of the shifter 60 operably controlled by a convenient hand-lever designated in a general way by *F*. This

hand-lever *F* is shown fulcrumed at its end by a pin or stud indicated by *7* to an elevated portion of the bed-plate *B* and as engaging with a pin *8* extending from the shifter bar and passing through an elongated opening *8*^a 70 in the hand-lever. Preferably a locking device will be combined with the hand-lever *F* for retaining it in a definite position corresponding to an adjusted position of the shifter bar *6*. The device here shown comprises a detent *9* (see Figs. 6 and 8) thrust outward through the bore of an opening in the extension *9*² (see the latter figure) by a spring *9*³ into engagement with a notch forming one of a series of notches *10* presented by 75 a locking-plate *10*^a. The notched portion of this locking-plate *10*^a preferably has in general a curved outline as seen in Fig. 6, the better to secure a proper action of the detent *9*, which detent it is evident from the foregoing description, while being held yieldingly in engagement with a notch, yet permits the lever *F* to be turned upon its fulcrum to bring the detent into another notch corresponding to the movement of the shifter bar 80 *6* for the purpose of bringing another die to the type-forming point.

Referring now to the illustrated construction for engaging the die-shifter *E* with a die-bar *D*, the shifter-bar *6* is provided with a cross slot *6*^e adapted to engage with a projection or tooth *6*^b, formed at the end of each die-bar by cross notching the same, (see *6*^e, Fig. 2 and Figs. 27, 29 and 30,) when the head *C* is rotated to bring the die-bar into 100 line with the sliding-bar; hence in this position of the parts a movement of the shifter bar serves to slide the die-bar forward in its guide-way, in which it is retained from lateral displacement by the previously-mentioned longitudinal rib *d*², the bottom surface of the guide space forms the reaction surface for the die-bar and taking the thrust of the latter during the operation of type-forming.

The normal or inoperative position of a 110 die-bar axially of the head *C* is indicated in Fig. 2 and from this figure it will be noticed that the cross-notch *6*^c in the die-bar referred to as forming the tooth *6*^b on the latter is opposite a plate *11*. In this position— 115 that is the inoperative position—of the die-bars the head *C* may be rotated upon its axis from side to side, the plate *11* extending radially inward to engage with the cross-notch *6*^c in each die-bar on each side of the 120 slot *11*² therein through which slot the shifter-bar *6* moves upon operating the hand-lever *F*, (see, for instance, Fig. 10, and the detailed views in Figs. 24, 25 and 26). The plate *11* therefore acts as a means for locking all the die-bars from lengthwise movement, except that particular one which is brought into line from the shifter-bar *6* 125 and automatically engaged therewith by the turning of the head *C* upon its axis. For— 130

thermore, it will be noticed on examining Fig. 2 that notch 6^c in the die-bar indicated (which die-bar is typical of all the others) is of sufficient depth to permit the entering 5 portion of the shifter-bar 6 to pass inward beyond the edges of the axial groove in the head C forming the guideway for the die-bar; hence when the head has been turned to bring the die-bar in line with the shifter- 10 bar and the latter has been moved to shift a die-bar lengthwise this entering portion will positively lock the head from further rotation until the die-bar has again been brought to its original position, as shown in Fig. 2. 15 In other words when the head C is being adjusted rotarially to bring any particular die-bar D into position, all the die-bars as well as the shifter-bar 6, are positively locked from lengthwise movement, and in addition 20 while this latter bar is being moved lengthwise to adjust the die-bar the head is locked from rotarial adjustment. Each die-bar D is, in the present case provided with an ac- 25 cessory part or feed-plate 12 operating to regulate the amount of movement of the blank-feeding mechanism operating in a manner hereinafter referred to at length. An indicator device is also shown for facil- 30 itating the adjustment of the several dies d with relation to the blank during the opera- 35 tion of forming composed types upon its edge. This device, designated in a general way by G, comprises a pointer or arm 13 ex- 40 tends from the shifter bar 6 and movable to-and-fro with it across the face of an in- 45 dicator-plate 14, which, in the present form, is curved and is attached to an arm 15 whose hub portion 15^a is secured to the shaft 2 of the head C in the space between the fixed 45 arms 4^a, 4^b already mentioned. This in- 50 dicator-plate 14 is shown provided with lines of characters designated in a general way by g extending lengthwise of the plate and cor- 55 responding to the various dies upon the several die-bars D and the parts are so relation- 60 tioned that when the pointer 13 is brought opposite any particular character the corre- 65 sponding die has assumed its type-making position.

The present machine, as already stated, is adapted to form type-bars from a continuous rod or ribbon-like blank, designated herein in a general way by H, by first making types upon its edge and then severing portions provided with such types into lengths. The strip or rod H may be conveniently supplied to the machine from a coil or roll of the same, shown supported on a suitable reel designated in a general way by K. This 60 reel K may be rotatably mounted upon an arm 16 in an appropriate position to deliver the blank H to the guide-slot 17 of a guide-block 18, and to compensate for the changing of diameter of coil as the blank is consumed, 65 this arm 16 may be pivoted to the base

frame B, as shown, to permit it to swing from a position indicated in part full and part dotted lines in Fig. 5 to the dotted position therein indicated.

The blank H is fed in a positive manner 70 forwardly in the direction of its length to bring successive and definite portions of its edge into the type-forming point to permit of the formation of composed types thereon spaced at such distances from each other as 75 accord with the demands of the art. Such feed movements of the blank take place intermittently, since during the formation of any individual type as the present machine forms the lengthwise movement of the blank 80 is interrupted. The device herein illustrated for effecting this positive feed movement operates upon shoulders formed on the side face of the blank and in the stock thereof, and such shoulders are made progressively 85 along the length of the continuous rod during the feed movement thereof and afterward used to effect such movement.

As shown, particularly in Fig. 6, a single element suffices both to form these shoulders 90 by notching the blank and to engage with the shoulders so formed to feed the blank forwardly. This element as constructed in the present case consists of a screw 19 with a ratchet thread and provided with a number 95 of longitudinal flutes or scorings 19^b produc- 100 ing a series of teeth. These flutes preferably extend for only a part of the length of the screw, leaving a portion of the screw pro- 105 vided with an unmutated thread, which en- 110 gaging with the notches h^c (see particularly Fig. 23) facilitates the feeding movement of the blank. The screw 19 is suitably mount- 115 ed in the guide-block 18 to cut notches of a sufficient depth in the stock of the blank to 120 form ample shoulders with which the rear end of the screw may engage and is posi- 125 tively driven in the present case by the fol- 130 lowing mechanism: Attached to the shaft 19^c of the screw is a gear-wheel 19' engaging with a gear-wheel 20 driven by a gear-wheel 21 attached to a shaft 22 and meshing with a gear-wheel 23 fixed with relation to the gear- 135 wheel 20. This shaft 22 is mounted in suit- 140 able bearings in which it is turned under con- 145 trol of the mentioned feed element or plate 12 on a die-bar by the following described means: It may be premised at the outset that a forward feed movement of the blank H takes place in the present organization im- 150 mediately following the formation of a type and while the blank is being withdrawn from engagement with the die against which it has been forced during the type-forming opera- 155 tion. Proceeding now with a detailed de- 160 scription of the present feed mechanism, there is affixed to the shaft 22 a ratchet- 165 wheel 24, with the teeth of which is adapted to engage a spring-pressed pawl 25, (see particularly Fig. 16,) pivoted to a lever 26. 170

This lever 26 is fulcrumed intermediate its ends to a bracket-arm 27 extending from and movable with a carrier, designated in a general way by L, and designed to move a portion of the blank passing through the machine toward and against the dies brought successively into position to form types. The other end of the lever 26, that is, the opposite end to that to which the pawl 25 is pivoted, is adapted to bear against the edge of the feed element 12, consisting, as previously mentioned, of a plate extending lengthwise of each die-bar D.

On examining Fig. 16, which represents the carrier L in its lowermost position, it is evident that as the carrier moves upward in the direction of the stationary die-bar D the lever 26 will be tilted about the point at which it contacts with the surface of the feed element 12 in such a direction as to slide the pawl 25 idly over the teeth of the ratchet-wheel 24. A pawl-actuator is herein shown in the form of a link 28 extending upward through an opening in the base frame B and operative from a cam 29 affixed to an intermittently rotating shaft 30 (adverted to at length later) to move the pawl in the opposite direction and turn the shaft 22 in its bearings. This actuator it may be stated has been left upon the previous rotation of the shaft 30 in its lowermost position with a space between its cam-roller and the periphery of the cam 29, or at least the initial movement of the shaft when it starts rotating suffices to move the cam in a direction to permit the ascent of the cam-roller; hence the upward movement of the outer or pawl-carrying end of lever 26 will not be resisted by cam 29 or the actuator link, but the latter will be likewise elevated. When the carrier L now returns to its original or lowermost position, during the operation of the machine, the resistance to motion exerted by the shaft 22 and by reason of the fact that the pawl engages with a tooth of the ratchet-wheel will cause the inner end of the lever 26 to swing downwardly, carrying this end away from the feed-plate 12 and leaving the lever free to be swung about its fulcrum on the bracket-arm 27 by the action of rotating cam 29 transmitted through the actuator link.

Some types, and hence the dies for forming them, being ordinarily wider than others, it is essential for the production of satisfactorily composed types that feed movements of greater lengths be imparted to the blank for the wider types. This variation in the degree of feed movement may be secured by providing the feed-plate 12 with suitable depressions, designated in a general way by 12^a, properly related to the different dies, and the bottom of each of which depressions forms the contacting point for the end of the lever 26 with the feed-plate, for it is evident that as the carrier L rises the end of the lever

opposite one of these depressions meeting with no resistance until the bottom of the depression is reached will cause a less inclination of the lever and consequently the slipping of the pawl 25 over a less number of teeth than would result if the contact portion of the lever were opposite a flush or depressionless portion of the feed element. In the present case, the actuator-link 28 is slotted at 28^b to embrace the shaft 30, whereby the link is guided and controlled in its movement, and a crank-handle W, extending from a crank w, which in turn is secured to the shaft 22, may be provided for feeding the blank through the machine by hand.

It has been stated that the shaft 30 has an intermittent movement, that is, a movement effective for securing the proper sequence of operations as the present machine is organized and constituted. Such movement in the present organization results from the operation of the following constructive details under the control of the operator. To the main driving-shaft 32 of the machine, which may be provided with a pulley 33 for effecting its continued rotation and journaled in suitable bearings 32^a, 32^b, there is affixed a worm 34 engaging with and serving to rotate a worm-wheel 35 acting as driver for the mentioned shaft 30 but normally disconnected therefrom. The latter shaft is rendered operative from the main driving-shaft, however, when a catch or detent 36 at the end of a lever 37 is withdrawn from a shoulder formed by a notch 38 in a locking disk 39 affixed to the shaft 30. This lever 37 is shown fulcrumed intermediate its ends to a projection 37^a on the under surface of the bed-plate B and tiltable from the upper surface of the latter to release the locking disk 39 by means of a push-rod 40 extending through an opening in the bed-plate and surmounted by a finger piece 41. Normally, this push-rod 40 is elevated and the catch 36 held in a position to engage the notch 38 by an elevating spring 42. When, however, the push-rod 40 is depressed by the operator the locking disk is released and the rotating main driving-shaft 32 drives the shaft 30 through the engaged worm 34 and worm-wheel 35 through some suitable device. The construction here shown for causing the rotation of the shaft 30 from the worm-wheel 35 and which nevertheless permits the continued rotation of the worm-wheel when the shaft is locked from rotation comprises a frictional connection of the parts, to wit; the worm-wheel 35 is loosely mounted upon its shaft but somewhat adjustable lengthwise thereof to permit of the clamping of its hub against a collar 43 affixed to the shaft 30. The clamping means shown comprises a nut 43^b engaging with a threaded portion of the shaft and bearing against a washer 43^c between which and the

hub of the worm-wheel a friction washer 43^a is inserted, whereby, when the nut 43^b is screwed up and adjusted sufficiently tight, adequate friction is created to overcome the 5 resistance opposing the rotation of the shaft 30 and rotate the shaft when the locking disk 39 is disengaged; but when however engagement of this disk with the catch 36 takes place a sliding of the surfaces over each 10 other occurs during the worm-wheel rotation and the shaft 30 remains stationary. A check-nut 43' may also be provided for locking the nut 43^b in any position to which it may be turned in regulating the friction de- 15 vice.

The various movements necessary to form a type upon the edge of the blank H and to feed the same forward to bring another portion of the latter to the type-forming point 20 are effected in the illustrated machine during a single rotation of the shaft 30 occurring as the result of the depression of the lever 37, as above explained, until by the rotation of the shaft the notch on the locking disk 39 is 25 again brought around to engage with the catch of the lever. The movement of the carrier L, before alluded to, to press the edge of the blank against the die and its return movement, results from the rotation of the 30 shaft 30 through the action of appropriate mechanism, of which the following shown and described device is an instance: The shaft 30 is suitably mounted in bearings 44—44 to bring certain carrier-actuators, 35 herein shown in the form of cams 45—45, one at each end of the shaft, into proper relation with respect to the contact portions of the carrier and enable the latter to be lifted thereby. These contact portions 40 may advantageously consist of rollers 46—46, (see particularly Fig. 17,) suitably mounted adjacent to the ends of the guide-posts 47—47 extending from the carrier and each adapted to work through an opening extending 45 through a projection 47^a of the bed-plate B. (See particularly Fig. 11.)

Referring now to the construction of the carrier L and its various accessories, as illustrated, mounted thereupon is the guide-block 50 18 described as receiving the blank from the reel K and at its opposite end the carrier is provided with a second guide-block 49 having a slot 49^a adapted to similarly receive and support the blank. The opposite ends 55 of the carrier are connected by a cross piece 50, and it is during the passage of the blank from guide-block to guide-block across the intervening space that its edge is operated upon to form types and type-separating 60 spaces.

For the better support and sustainment of the blank against the pressure of the operating die and to hold it up to the latter during the type-forming operation, there is provided 65 a work-holder, designated in a general way

by M, having a lengthwise slot 51 in its upper face in line with the slots in the guide-blocks 18 and 49, against the sides and bottom of which the blank seats itself during the sub- 70 jection of its edge to the action of the die. 70

The foregoing operation by which the successive types are produced in the present machine results from an auxiliary movement imparted to that portion of the blank at and adjacent to which the type is being formed, 75 in addition to the compression of the blank by the type-forming die. While in the present embodiment the blank is movable toward the die, this particular relative motion is an instance of what may be termed in general a 80 relative movement of the members toward each other. Such auxiliary movement is designed to facilitate the complete filling of the crevices and hair-line spaces of the die cavity with the object of producing a clear-cut and 85 sharply defined type having surfaces compact and rendered dense; and to form, moreover, a type-block with a base portion strengthened where it connects with the stock of the blank. Such a mode of forming 90 types and the operative relation and advantages of the various features involved are fully set forth in applications filed by me on the 16th day of December, 1899, and on the 21st day of October, 1901, Serial Nos. 740,512 95 and 79,359, respectively, which may be referred to for a more detailed description. Suffice it here to say that this auxiliary movement is, in the present instance, imparted to the blank by oscillating the work-holder M to swing the blank portion about an axis extending longitudinally of the blank and located preferably in proximity to the impression surface of the finished type. The thrust of the work-holder M is in the present 100 construction taken upon a roller 52 mounted below the holder in the cross piece 50 of the carrier, and to enable the holder to fully swing to-and-fro in a direction crosswise of the blank, its lower bearing edges n, n may 110 be curved, as shown in Fig. 18.

To permit of the composite motion which the work-holder is designed to have—that is, an oscillatory swinging movement combined with a transverse feed movement toward the 115 die-head C—the work-holder may be provided at its ends with guide parts, here shown in the form of ribs or flanges 53 adapted to be guided in and slide lengthwise of corresponding grooves 53^b, 53^b in a member 54 at each 120 end of the holder, each of which members is journaled in a corresponding bracket 55, (see Fig. 20,) secured to the bed-plate B or other stationary part of the machine. Each bracket 55, furthermore, for the purpose of 125 confining its journaled member to a swinging movement, is provided with an annular groove 55^b in which is adapted to rock to and fro the correspondingly-formed journal portion 54^b of the member. 130

It is evident from this construction that while the work-holder is free to move toward the die-head C, it is at the same time at liberty to swing backward and forward if operated upon, both of which movements may take place concurrently. Both the bracket 55 and the member 54^b at each end of the work-holder are provided with comparatively wide slots 55^c to freely allow of the slight 10 twisting of the blank due to the swinging of that portion supported in the work-holder.

An oscillator, designated in a general way by N, is utilized in the present construction to impart a rapid oscillating motion to the 15 work-holder M, and in the construction shown, consists of a block 56 of suitable form sustained by pivot-pins 56^b, 56^b passing through and secured in openings in the mentioned upright 3 and a second upright 57 20 and entering corresponding pivotal recesses formed in the block 56, in which position the pins may be secured by check-nuts 56^c, 56^c. An oscillatory motion is given to the oscillator N through the medium of an oscillator-link 25 58 pivoted at its upper end to an arm 59 extending from the oscillator and at its lower end carrying an eccentric strap 60 embracing an eccentric 60^a secured to the main driving-shaft 32. Motion is transmitted from the 30 oscillator N to the work-holder by a link 61 connected at the holder end to the projections 55^d, 55^d extending from the holder.

Provision exists in the present machine for automatically varying the character of the 35 oscillatory movement during the period in which such movement is imparted to the work-holder for the purpose, as set forth in the previously-referred to applications, of more effectually producing a perfectly-formed type. To this end the oscillatory movement preferably diminishes in amplitude or extent of vibration during the later 40 stages of the type-forming operation, that is, as the type is nearing completion, and it may 45 advantageously altogether cease just prior to the termination of the transverse feeding movement of the blank and die. This particular order of operation is brought about according to the present construction by 50 making the connection of the link 61 with the oscillator shiftable along the oscillator-block toward and away from the axis of oscillation of the latter. As shown, the oscillator-block 55 is formed with curved guides n², n², along which guides is adapted to move a slide 62 to 55 which the link 61 is connected, and as means of shifting the slide as aforesaid, a vibratory arm 63 pivoted to a bracket (see Fig. 4) and connected by a link 65 to the link 61 serves 60 through the movement of a cam 66 attached to the intermittently-driven shaft 30, and bearing against a cam-roller 67 on the vibratory arm 63, to shift the slide in one direction, while the various parts tend to 65 stantly move in the reverse direction or to

their original positions, through the tension of spring 69 connected to the bed-plate or stationary part of the machine. It is evident now that when the straight line connecting the two pivotal points of the oscillator, 70 that is, that line which forms its axis of oscillation, coincides with the pivotal axis of the slide 62, the work-holder M will have substantially no oscillatory movement, but that as the slide 62 is moved farther and farther 75 from this axis and toward the end of the oscillator, an oscillatory motion will be imparted to the work-holder increasing in amplitude as the slide moves outward; hence by giving a proper configuration to the operative 80 surface or edge of the cam 66 a desired variation in such movement may be effected.

The machine illustrated in the drawings accompanying the present specification is adapted to make typebars whose lengths 85 vary between certain prescribed maximum and minimum dimensions, producing typebars having the general appearance exhibited in Fig. 32 when assembled, where a short typebar and a long typebar are shown 90 together with other bars of intermediate lengths. These bars as they come from the machine may afterward be subjected to some suitable process or treatment whereby they may be all brought if desired to the 95 same length; for instance, there is shown, described, and claimed in an application filed by me on April 9, 1900, Serial No. 12,164, and entitled "Bar lengthening machines", a machine for treating typebars of 100 different lengths for the purpose of bringing them all to the same linear dimension, and the machine therein set forth may be utilized for the treatment of the product from the present machine to render the lengths of the 105 individual bars uniform.

As constructed, organized, and operating herein, there is combined with other mechanism what I may term a gage designed to make known to the operator the point at 110 which a feed movement of the blank has taken place corresponding in amount to the minimum length of typebar which the machine is set or adapted for making. It should be stated at the outset that excess 115 material rolled from the edge of the blank and beyond the side lines thereof through the action of the oscillatory movement of the work-holder while the successive dies are in contact with the edge of the blank and during the formation of the customary type-separating spaces, is stripped or trimmed from the stock of the blank to bring the sides of the continuous typebar into substantial 120 parallelism by some suitable means, that 125 shown consisting of a cutting instrument 70, 70 located at the sides of the blank adjacent to its edges and retained in position in the openings in projecting arms 49^b, 49^b of the guide-block 49 by means of suitable fasten- 130

ing devices; for instance, screws 49°, 49°. After passing through the space between the cutting instrument 70, 70 the bar has been deprived of its excrescences and is ready to be 5 separated into typebar lengths. Passing now to a description of the before-mentioned gage, a toothed-wheel 71 is mounted upon a shaft 71^b to engage with the notches *h*² formed in the blank H. Such mounting is 10 shown most clearly in Figs. 22 and 23 to comprise a bracket 71^a extending from the bed-plate B. The circumference of the toothed wheel 71 is substantially equal to the minimum length of a typebar which it is desired 15 shall be made, so that the moving blank acting as a driver for the wheel will have caused the latter to turn through a full rotation when a length of the blank has been fed forward corresponding to the minimum length 20 of a typebar. Upon the completion of this rotation, an arm 72, normally rotating in unison with the shaft 71^b, but frictionally connected therewith by suitable means embodying a friction washer 71', for instance, 25 to permit the arm to remain stationary while the shaft continues in rotation, for a purpose appearing later, comes in contact with a shiftable stop shown as a pin 73 extending from a lever 74 fulcrumed intermediate 30 its ends to a post 75 and normally held by a spring 76 in a position in which the pin extends across the path of the moving arm 72. Such position for the lever 74, that is, its normal position is determined by a fixture 35 73^b.

From the foregoing construction it is evident that even though the arm 72 has contacted with the stop-pin 73, the toothed wheel 71 is still free to rotate under the 40 driving action of the notches in the blank with which it is in engagement. The occurrence of this contact, however, serves to indicate to the operator that further procedure on his part should be such as to fit the composed types just made for producing a properly closed line of composition, which he may 45 properly do by forming the necessary types to complete the syllable or word, if not already completed, or by forming an impression character or type adapted for making a dash. In any event, whether something additional remains to be done to properly 50 close the line of composed types when contact, as aforesaid, has taken place, or a word 55 has been finished coincident with such contact, a space or depressed section is still to be made in the edge of the blank across which the stock of the blank will afterward be divided to form a typebar, which space I may 60 designate as the division space. (See *x*, Figs. 12 to 15, inclusive.) The relative position of the various parts at this stage is 65 shown in Fig. 12, where it will be noticed that the arm 72 is in contact with the stop-pin 73, this figure representing in other words

the position of the parts just prior to the making of a space at the point of division. For the purpose of making this division space, I preferably utilize a die similar to those used for making a space between 70 words or letters, that is, a space in the ordinary composed matter, (which space may vary in width as readily understood,) employing a full portion of a die-bar and rolling off a section of the edge transversely of the 75 blank to depress the surface of such portion below the common level of the type impression surfaces. Such a portion is shown at *x'* in Fig. 30. It will be noticed in this figure, also, that this particular die-bar is 80 provided at its opposite end with an extension *y*, which, when the die-bar is adjusted to bring the portion *x'* over the blank, is adapted to contact with the free end of the lever 74 and turn the same upon its fulcrum 85 against the tension of spring 76, thereby withdrawing the stop-pin 73 from the path of the arm 72. With the die-bar in this position, and agreeably to the previously-explained mode of operation, the push-rod 90 40 is depressed by the operator, resulting in the formation of the division space, followed by the descent of the carrier L and the simultaneous advance of the blank. The relative position now assumed by the parts 95 is represented in Fig. 13, in which the lever 74 is represented as having been turned upon its fulcrum by the before-mentioned die-bar moved from a position indicated by Y in Fig. 12 to the position Y' in Fig. 13. The formation of this division space *x* completes a typebar length, although the cutting-off mechanism upon its next operation will not, as the machine is herein organized, sever the bar across the space just made but across a corresponding space which was previously 100 made. In this connection it should be stated that it is deemed preferable to separate a typebar from a strip or ribbon by means other than shearing; as sheared ends 105 are almost invariably more or less distorted in form; such distortion being, at least in some instances, sufficient in degree to affect the shapes or positions of types formed contiguous to said ends; while, should sufficient 110 material be left on the typebar-end to prevent distortion of the adjacent type, another and separate operation would be found necessary to machine off said surplus stock. For this reason I have, in my present invention, deemed it advisable to adopt a cutting-off mechanism which will in no wise distort any portion of the material, either of the typebar or of the remaining end of the strip; but will, on the contrary, leave the ends, 115 both of the typebar and of the ribbon or strip, in the exact form required for use. In order to effect this object, it will ordinarily be found necessary to remove a section of 120 stock from the ribbon or strip immediately 125 130

adjacent to the finished length which forms the typebar. An illustration is given herein of one form of such mechanism which form may be described as follows:

5 The cutting-off mechanism herein set forth embodies a controller normally held in an inoperative position by the blank and consisting of a lever 77 pivoted to a bracket 78 to swing in the plane of the type-blocks upon 10 the edge of the blank and toward and against which blocks a finger 77^b on the lever is forced by a spring 77^c, as shown in Figs. 12 and 13. The contacting end of finger 77^b is of such size and shape as to render it incapable of entering any of the spaces between the 15 composed types adapted for forming letters or words as they exist in ordinary composition, but when the division-space *x* comes opposite the end of the finger the latter slips 20 thereinto, in which position (see Fig. 14) it contacts with and swings the releasing lever 79 on its fulcrum 79^b. This lever 79, as shown, lies directly opposite the finger 77^b of the lever 77 on the opposite side of the blank 25 and in the plane of movement of that finger, being held in its normal position against a stop 79^c by the tension of a spring 79^d. The detent 79^e on the releasing lever 79 normally engages with an arm 80 extending from a 30 shaft 81 journaled in bearings 81^b supported by the bed-plate B, and restraining the same from rotation. Such rotation of the shaft 81 tends to take place through the action of the rotating worm 82 affixed to the main driving- 35 shaft of the machine and engaging with a worm-wheel 83 frictionally connected to the former shaft. The connection of this worm-wheel 83 with its shaft may be analogous to that described with reference to the connection 40 of the worm-wheel 85, embodying as set forth in the drawings a friction washer 83^b pressed against the hub of the worm-wheel by means of nut 83^c locked in place by a check-nut 83^d. Assuming now that the 45 detent 79^e has been withdrawn from engagement with the arm 80 and the shaft 81 as a result set in rotation, a crank disk 84 on the end of the shaft operates through a crank-pin 85 and a connecting-rod 85^b to actuate a 50 slide 86, to an extension 86^b of which the connecting-rod is pivoted. This slide 86 is suitably mounted in guideways 86^c to travel to-and-fro in a direction transverse to the length of the blank H. Mounted in a suitable 55 bearing 87^b supported on the slide 86 by a bracket 87^c is an arbor carrying a saw 87 located just below the finger 77^b on the lever 77 and in line with the releasing lever 79. The arbor of this saw 87 is shown provided 60 with a pulley 88 designed to be rotated from some convenient source of power, at least during the time the slide 86 upon which it is mounted is being traversed. Slotted uprights 89, 89 on the guideway 86^c are adapted 65 to receive the blank and guide the same as it

leaves the machine, and the throw of the crank-pin 85 is sufficient to cause an adequate transverse movement of the saw 87 to sever the stock of the blank across a division space and thus form a typebar.

It is evident upon a little reflection that the operation of the cutting-off mechanism as herein constructed and operated is automatic in that it is set in motion and governed in its operation by the arrival of a division space *x* opposite the finger 77^b of the lever 77. This cutting-off operation therefore may occur during the feed movement of the blank, and to prevent distortion of the latter and to insure the freedom of movement of the various parts concerned, the saw is preferably movable with the blank when the slide 86 is moving in its guideways. For this purpose the guideways 86^c for the slide 86 may be formed upon or in a fixture extending from a 85 sliding-plate 90, as shown, which plate 90 is adapted to have a motion in line with the blank H, by mounting the same, for instance, in guideways 90^b extending from or formed in the bed-plate B. It is evident, furthermore, that the lever 77 after its finger 77^b has swung across the blank and into the division space must partake of any longitudinal movement which the blank has while the finger is so situated, as otherwise a rupture or 95 distortion of the types would result. The bracket to which the lever is pivoted is therefore in this organization attached to the sliding-plate 90, and the finger 77^b after it engages with the space acts to drag the plate 100 and the various supported parts along with the moving blank until the finger has been disengaged from the slot. This disengagement is brought about in the present construction by reason of the contact of the free 105 end of the lever 77, which as shown consists of a cam portion 77^d, with a cam-roller 77^e supported upon a fixed arm 91, (see for this position Fig. 14,) whereupon further movement of the blank results in the coaction of 110 this roller 77^e and the cam portion 77^d and the withdrawal of the arm 77^b from the space *x*. The sliding-plate 90 is now free to be returned to its original position with the cutting-off mechanism ready to again operate, by the tension of a spring 92, which acts to bring an arm 93 on the plate in contact with a stop, here shown to be an adjustable screw 94 extending from a fixed portion of the machine. To permit of this movement 120 of the sliding-plate in a direction in line with the longitudinal movement of the blank, that is, in a direction transverse to the line of movement of the slide 86, the crank-pin 85 is elongated, as shown, from end to end of 125 which pin the connecting-rod may slide.

A machine constructed and organized in accordance with the foregoing, operates substantially in the following manner: Assuming that a coil of appropriate typebar-blank 130

has been placed upon the reel K and the end has been introduced into the guide-slot 17, the crank-handle W is then operated to rotate the feed-screw 19 and feed the blank 5 through the slot in the work-holder M and into contact with the toothed wheel 71, which latter is assumed to be in the position represented in Fig. 13, that is, in a position corresponding to the beginning of the motion 10 of the toothed or measuring wheel 71. The parts are now ready to proceed with the formation of types on the edge of the blank. By the aid of the indicator G on the turning of the die-head by means of the handle C^a a 15 desired diebar may be brought into alignment with the slot 11² in the locking-plate 11, when by a manipulation of the handle-lever F the diebar may be shifted and the desired die brought to the type-forming point and 20 over the blank. In this position the head and the diebar are retained by the previously-described locking devices comprising the spring arm 5 and the spring-pressed detent 9. The main shaft 32, it will be understood 25 stood, is rotating continuously. The next step in the production of a type upon the edge of the blank is the depression of the key or finger piece 41, resulting in the tilting of the lever 37 and the release of the locking disk 39. Shaft 30 now rotates through the 30 action of the worm 34 by reason of its engagement with the worm-wheel 35 and the carrier L is lifted through the action of the cams 45, 45, carrying with it the work-holder M and pressing that portion of the blank in the slot thereof against the adjusted die in the die-head C. Simultaneously with this upward movement of the carrier the bracket arm 27 attached thereto raises the 35 pawl 25, causing it to slide over the teeth of the ratchet-wheel 24, as well as lifting the actuator-link 28. Some time after the parts according to the preferred sequence of operations have assumed a position in which the 40 blank edge has been brought into contact with the die, the slide 62 of the oscillator N is shifted from its normal position in which the pivotal axis of the oscillator-link 61 coincides with the axis about which the 45 oscillator vibrates toward the end of the oscillator. Owing to this normal coincidence of the two axes no oscillatory motion is imparted to the work-holder, even though the oscillator be in constant motion from the 50 rotating eccentric 60^a attached to the rotating main driving-shaft 32 through the connections extending between this eccentric and the oscillator. The vibratory motion of the work-holder will commence, however, 55 as aforesaid, when the cam 66 tilts the lever 63 to shift the slide in the oscillator. The amplitude of such vibratory or oscillatory motion increases with the progress of the carrier movement in compressing the blank 60 more and more against the die until as the

carrier approaches the limit of its upward movement the oscillatory motion will preferably, as already pointed out, grow less and substantially cease just prior to the attainment by the carrier of its utmost highest position through the action of the cam 66 in returning the slide to its original or normal position. The carrier L is now ready to be returned to its original or lowermost position as the cams 45 and 45 continue to rotate 70 under the tension of spring 69. Some time prior to the completion of the full rotation of the shaft 30, however, cam 29 will have contacted with the cam-roller 31 on the actuator-link 28 and by the further rotation of the shaft 30 to which it is attached will operate to depress the actuator-link 28 and rotate the feed-screw 19, thereby feeding the blank H a step forward to an extent determined by the feed element 12, as already explained. 75 When the shaft 30 has completed its rotation it will be arrested from further movement by the engagement of the detent 34 on the lever 37 with the shoulder of the locking disk 39, whereupon the parts have assumed their 80 normal position proper for the production of another type, or a space, which may be produced in a similar way by adjusting the die-head C and the appropriate die-bar D thereon to bring the desired die or space-forming 85 portion on the die-bar into the type-forming point. Such in general is the procedure in forming composed matter along the edge of the blank until arm 72 has come in contact with the stop-pin 73 upon lever 74, when, it 90 will be readily understood from the preceding description, the time has arrived to complete the line of what will eventually form the composed types of a typebar. Assuming this to have been done a division space has 95 finally to be formed to complete the bar. 100

The head C is now adjusted to bring that diebar D provided at one end with the previously-mentioned extension y and at the other with the division space forming die x', 110 into a position in which it may be shifted longitudinally of the head by the shifter-bar 6. When this shifting of the die-bar has been done the extension y coming in contact with the lever 74 swings the same upon its 115 fulcrum and carries the stop-pin 73 out of the path of the arm 72, thus permitting the space to be formed and causing the arm to take a position corresponding to its initial position at the beginning of the formation of a typebar. The operation of forming this space will be readily understood from what has been said and need not be further entered into here. Beyond the type-making portion of the machine the ribbon passes between the 120 cutting instruments 70, 70, which operate to trim the same and remove the material forced beyond the sides by the rolling action of the die. Assuming, lastly, that a succession of types and spaces have been made and that a 130

division space has come opposite the finger 77^b, this finger enters the space, actuating the releasing lever 79, which is followed by the rotation of shaft 81 through the action of 5 the engaging worm 82 and worm-wheel 83. The crank disk 84 now rotates, serving to traverse the rotating saw 87 across the stock of the blank at the point where the division space has been made and sever a typebar 10 length. At the same time that this cutting-off action occurs the various parts may travel with the blank, the sliding plate 90 being carried in this direction by reason of the engagement of the finger 77^b with the division space 15 until, in consequence of such forward movement, the cam portion 77^d of the lever 77 comes in contact with the cam-roller 77^e, whereupon the finger 77^b is withdrawn from the space and the parts returned to their 20 normal position by the spring 92. The motion of the shaft 81 upon the completion of its rotation is arrested by reason of the engagement of the detent 79^e with the arm 80 extending from the shaft. The waste portion 25 at the beginning of the blank may be removed from the first typebar formed by any suitable means, and after the types have once begun to be formed upon the blank it may substantially all be used to form finished 30 typebars after and in the manner described.

Having described my invention, I claim—

1. The combination with a type making instrumentality, of means for feeding a blank forward and past said instrumentality, means 35 for automatically severing, under the control of a blank in its feed movement forward, a typebar therefrom.

2. The combination with a plurality of adjustable type making instrumentalities, of 40 means for feeding a blank for bringing successive portions thereof past the working point of said instrumentalities, a stock-removing saw for automatically severing, under the control of a continuous blank in its 45 said feed movement, a typebar therefrom.

3. The combination with a die, of feed mechanism for imparting a lengthwise forward feed movement to a continuous blank, and a stock-removing saw for automatically severing, under the control of the blank in such feed movement a typebar therefrom.

4. The combination with a plurality of adjustable dies, of feed mechanism for imparting a forward lengthwise feed movement to a 55 continuous blank, and means for automatically severing, under the control of the blank in such forward feed movement, a typebar therefrom.

5. The combination with a die, of means 60 for forcing the die and a ribbon-like blank one against the other, and means under the automatic control of the blank for severing while the blank is being acted upon by the die a typebar therefrom.

6. The combination with a plurality of

dies, of means for forcing a selected die and a ribbon-like blank one against the other, and means controlled by the blank during its normal feed movement for severing therefrom a typebar while said blank is being 70 acted upon by a die.

7. The combination with a plurality of type making dies, of means for feeding a blank for bringing successive portions thereof past the working point of said dies, means for 75 severing typebars from said blank, means actuated by the blank for controlling said severing means, and means for concurrently actuating said severing means and bringing a selected die and the blank into type forming 80 relation.

8. The combination with a die, of means for forcing the die and a continuous blank one against the other, means for severing type bars from the blank, means automatically actuated by the blank for controlling the 85 severing means, and means for actuating said severing means concurrently with the die action.

9. The combination, with a die, of means 90 for forcing the die and a blank against each other; means for imparting oscillatory movement to one of such members during the type-forming period; and means for severing the stock of the blank to form a typebar.

10. The combination, with a die, of means for forcing the die and a blank against each other; means for imparting oscillatory movement to one of such members during the type-forming period; and means for severing 100 a typebar from a ribbon or bar by removing a section of stock.

11. The combination, with a plurality of adjustable dies, of means for forcing a die and a blank against each other; means for 105 imparting oscillatory movement to one of such members during the type-forming period; and means for severing the stock of the blank to form a typebar.

12. The combination, with a plurality of 110 adjustable dies, of means for forcing a die and a blank against each other; means for imparting oscillatory movement to one of such members during the type-forming period; and means for severing a typebar from 115 a ribbon or bar by removing a section of stock.

13. The combination, with a die, of feed mechanism for imparting lengthwise movement to a blank; means for forcing the die 120 and a blank against each other; means for imparting oscillatory movement to one of such members during the type-forming period; and means for severing the stock of the blank to form a typebar.

14. The combination, with a die, of feed mechanism for imparting lengthwise movement to a blank; means for forcing the die and a blank against each other; means for 125 imparting oscillatory movement to one of 130

- such members during the type-forming period; and means for severing a typebar from a ribbon or bar by removing a section of stock.
- 5 15. The combination, with a plurality of adjustable dies, of feed mechanism for imparting lengthwise movement to a continuous ribbon-like blank; means for forcing a die and the blank against each other; means for imparting oscillatory movement to one of such members during the type-forming period; and means for severing the stock of the blank to form a typebar. 70
- 10 16. The combination, with a die, of means for forcing the die and a blank against each other; means for imparting a varying oscillatory movement to one of such members during the type-forming period; and means for severing the stock of the blank to form a typebar. 75
- 15 17. The combination, with a die, of means for forcing the die and a blank against each other; means for imparting a varying oscillatory movement to one of such members during the type-forming period; and means for severing the stock of the blank to form a typebar. 80
- 20 18. The combination, with a die, of means for forcing the die and a blank against each other; means for imparting a varying oscillatory movement to one of such members during the type-forming period; and means for severing a typebar from a ribbon or bar by removing a section of stock. 85
- 25 19. The combination, with a plurality of adjustable dies, of means for forcing a die and a blank against each other; means for imparting a varying oscillatory movement to one of such members during the type-forming period; and means for severing the stock of the blank to form a typebar. 90
- 30 20. The combination, with a plurality of adjustable dies, of means for forcing a die and a blank against each other; means for imparting a varying oscillatory movement to one of such members during the type-forming period; and means for severing the stock of the blank to form a typebar. 95
- 35 21. The combination, with a die, of feed mechanism for imparting lengthwise movement to a continuous ribbon-like blank; means for forcing the die and the blank against each other; means for imparting a varying oscillatory movement to one of such members during the type-forming period; and means for severing the stock of the blank to form a typebar. 100
- 40 22. The combination, with a plurality of adjustable dies, of feed mechanism for imparting lengthwise movement to a continuous ribbon-like blank; means for forcing a die and the blank against each other; means for imparting oscillatory movement to one of such members decreasing in amplitude during the later stages of the type-forming period; and means for severing the stock of the blank to form a typebar. 105
- 45 23. The combination, with a die, of means for forcing the die and a blank against each other; means for imparting oscillatory movement to one of such members decreasing in amplitude during the later stages of the type-forming period; and means for severing the stock of the blank to form a typebar. 110
- 50 24. The combination, with a die, of means for forcing the die and a blank against each other; means for imparting oscillatory movement to one of such members decreasing in amplitude during the later stages of the type-forming period; and means for severing a typebar from a ribbon or bar by removing a section of stock. 115
- 55 25. The combination, with a plurality of adjustable dies, of means for forcing a die and a blank against each other; means for imparting oscillatory movement to one of such members decreasing in amplitude during the later stages of the type-forming period; and means for severing the stock of the blank to form a typebar. 120
- 60 26. The combination, with a plurality of adjustable dies, of means for forcing a die and a blank against each other; means for imparting oscillatory movement to one of such members decreasing in amplitude during the later stages of the type-forming period; and means for severing a typebar from a ribbon or bar by removing a section of stock. 125
- 65 27. The combination, with a die, of feed mechanism for imparting lengthwise movement to a continuous ribbon-like blank; means for forcing the die and the blank against each other; means for imparting oscillatory movement to one of such members decreasing in amplitude during the later stages of the type-forming period; and means for severing the stock of the blank to form a typebar. 130
28. The combination, with a die, of feed mechanism for imparting lengthwise movement to a continuous ribbon-like blank; means for forcing the die and the blank against each other; means for imparting oscillatory movement to one of such members decreasing in amplitude during the later stages of the type-forming period; and means for severing a typebar from a ribbon or bar by removing a section of stock.
29. The combination, with a plurality of adjustable dies, of feed mechanism for imparting lengthwise movement to a continuous ribbon-like blank; means for forcing a die and the blank against each other; means for imparting oscillatory movement to one of such members decreasing in amplitude

during the later stages of the type-forming period; and means for severing the stock of the blank to form a typebar.

30. The combination, with a die, of an oscillatory work-holder, and means for passing a continuous ribbon-like blank through the work-holder with an intermittent or step-by-step motion.

31. In a machine for forming type upon a ribbon-like blank, the combination of a die; a work-holder oscillatable transversely of the blank; and means for passing said blank through the work holder.

32. In a machine for forming type upon a ribbon-like blank, the combination of a die; a work-holder oscillatable transversely of the blank; and means for passing said blank through the work-holder with an intermittent or step by step motion.

33. In a machine for forming type upon a ribbon-like blank, the combination of a plurality of dies; a work - holder oscillatable transversely of the blank; and means for passing said blank through the work-holder.

34. The combination, with a carrier, of a die; means for moving the die and the carrier toward and away from each other; a work-holder supported upon the carrier; and means for feeding a continuous ribbon-like blank across the carrier and through the work-holder.

35. The combination, with a carrier, of a die; means for moving the die and the carrier toward and away from each other; an oscillatory work-holder supported upon the carrier; and means for feeding a continuous ribbon - like blank across the carrier and through the work-holder.

36. The combination, with a carrier, of a die; means for moving the die and the carrier toward and away from each other; an oscillatory work-holder supported upon the carrier; means for feeding a continuous ribbon-like blank or rod across the carrier and through the work-holder; and means for imparting an oscillatory movement to the work-holder at some time during the relative movement of the die and the work-holder toward each other.

37. The combination, with a carrier, of a die; means for moving the die and the carrier toward and away from each other; an oscillatory work-holder supported upon the carrier; means for feeding a continuous ribbon-like blank or rod across the carrier and through the work-holder; and means for imparting an oscillatory movement to the work-holder at some time during the relative movement of the die and the work-holder toward each other diminishing in amplitude of vibration during the later stages of the movement of the die and blank toward each other.

38. The combination, with a carrier, of a die; means for moving the die and the carrier

toward and away from each other; an oscillatory work-holder supported upon the carrier; an oscillator for imparting movement to such work-holder; a connecting-link extending between the oscillator and the work-holder; and means for feeding a continuous ribbon - like blank across the carrier and through the work-holder.

39. The combination, with a carrier, of a die; means for moving the die and the carrier toward and away from each other; an oscillatory work - holder supported upon the carrier; an oscillator for imparting movement to such work-holder; a connecting-link extending between the oscillator and the work-holder; a slide movable lengthwise of the oscillator to which said connecting-link is secured; means for shifting this block away from and toward the axis of oscillation of the oscillator whereby the work-holder may normally remain at rest and be caused to oscillate as the slide is moved outward; and means for feeding a continuous ribbon-like blank across the carrier and through the work-holder.

40. The combination, of a carrier; a die; an oscillatory work-holder; an oscillator for imparting movement to the work-holder; a link connecting the work-holder with the oscillator; a slide movable lengthwise of the oscillator to which said connecting-link is secured; a shaft and cams thereon for moving the die and carrier toward each other and shifting said block lengthwise of the oscillator; and means for feeding a continuous ribbon-like blank lengthwise of the work-holder.

41. The combination, with a carrier; of a die; means for moving the die and the carrier toward and away from each other; an oscillatory work-holder supported upon the carrier; an oscillator for imparting movement to such work-holder; a connecting-link extending between the oscillator and the work-holder; a slide movable lengthwise of the oscillator to which said connecting-link is secured; means for shifting this block away from and toward the axis of oscillation of the oscillator whereby the work-holder may normally remain at rest and be caused to oscillate as the slide is moved outward; means for feeding a continuous ribbon-like blank across the carrier and through the work-holder; and a key for rendering said means operative to shift said slide.

42. In a machine for forming types upon a ribbon-like blank, the combination of a die; a work-holder oscillatable transversely of the blank and having a slot arranged for the passage of said blank, and in which a portion of the blank is supported during the operation of the die to form a type.

43. In a machine for forming types upon a ribbon-like blank, the combination of a die; a work-holder oscillatable transversely of the blank and having a slot arranged for the pas-

sage of said blank and in which a portion of the blank is supported during the operation of the die to form a type; and means for moving said die and the work-holder toward each other.

44. In a machine for forming types upon a ribbon-like blank, the combination of a die; a work-holder oscillatable transversely of the blank, and having a slot arranged for the passage of said blank and in which a portion of said blank is supported during the operation of the die for forming a type; means for moving the die and the work-holder toward each other; and means for feeding the blanks through the slot in the work-holder.

45. In a machine for forming types upon a ribbon-like blank, the combination of a work-holder oscillatable transversely of said blank; and a carrier on which the work-holder is supported and which is adapted to move the work-holder toward a type-forming die.

46. In a typebar machine, the combination of a carrier and a typebar-blank holder movable with the carrier and having a separate and independent motion, and means for imparting each of said movements.

47. The combination, of a work-holder provided with a slot; a carrier supporting said holder and with which the holder is movable; members in which the work-holder is guided when moved by said carrier; and fixed parts in which the said members are journaled.

48. In a typebar machine the combination with a die and means for operating the same to force excess material beyond the planes of the sides of a blank, of a cutting instrument for trimming off such material, means for feeding the blank past the working point of said die and past the working point of said cutting instrument.

49. In combination with a die operating to force excess material beyond the planes of the sides of a blank, of a cutting instrument for trimming off such material, and means for feeding a continuous ribbon-like blank and causing such instrument to operate.

50. In a machine for forming type upon a ribbon-like blank, the combination of a work-holder oscillatable transversely of the blank; a cutting instrument; and means for feeding the blank through the work-holder and against the cutting instrument.

51. In a typebar-machine, a work-holder, a carrier, and a friction roller mounted upon the carrier and on which the said holder bears.

52. In a typebar-machine, a work-holder, in combination, with a carrier; means for feeding a continuous ribbon-like blank across the carrier and through the work-holder; and a cutting instrument in contact with which the blank passes after issuing from the holder.

53. In a typebar-machine, a carrier provided with guide-blocks, in combination,

with a work-holder located between the guide-blocks and a cutting instrument for trimming the blank.

54. The combination of a rotatable member; a die-carrier movable axially of said member; and a plurality of impression devices mounted on said die-carrier.

55. The combination of a rotatable member; a die-carrier adjustably movable axially of said member; and a plurality of impression devices mounted on said die-carrier.

56. The combination of a rotatable member; a plurality of die-carriers movable axially of said member; and a plurality of impression devices mounted on each of said die-carriers.

57. The combination of a rotatable member; a plurality of die-carriers adjustably movable axially of said member; and a plurality of impression devices mounted on each of said die-carriers.

58. The combination of a rotatable member; a die-carrier movable axially of said member; a plurality of impression devices mounted on said die-carrier; and a die-carrier shifter.

59. The combination of a rotatable member; a plurality of die-carriers movable axially of said member; a plurality of impression devices mounted on each of said die-carriers and a die-carrier shifter.

60. In a machine for forming types upon a ribbon-like blank, the combination of a device adapted to impress a character upon said blank; and a work-holder oscillatable a plurality of times transversely of said blank during the operation of impressing the device.

61. In a machine for forming type upon a ribbon-like blank, the combination of a device adapted to impress a character upon said blank; a work-holder oscillatable a plurality of times transversely of said blank during the operation of impressing the device; and means for passing the blank through the work-holder.

62. In a machine for forming type upon a ribbon-like blank, the combination of a device adapted to impress a character upon said blank; a work-holder oscillatable a plurality of times transversely of said blank during the operation of impressing the device; and means for passing the blank through the work-holder with an intermittent or step-by-step motion.

63. In a machine for forming type upon a ribbon like blank, the combination of a plurality of dies adapted to impress characters upon said blank; a work holder oscillatable a plurality of times transversely of said blank during each operation of impressing a die; and means for passing the blank through the work-holder.

64. In a machine for forming type upon a ribbon-like blank, the combination of a plurality of devices adapted to impress charac-

36 tters upon said blank; a work-holder oscillatable a plurality of times transversely of said blank during each operation of impressing a device; and means for passing the blank 5 through the work-holder, with an intermittent or step-by-step motion.

65. In a machine for forming type upon a ribbon-like blank, the combination of a device adapted to impress a character upon 10 said blank; and a work-holder oscillatable a plurality of times transversely of said blank during the operation of impressing the device and having a groove arranged for the passage of said blank in which groove a 15 portion of the blank is supported during the operation of the device to form a type.

66. In a machine for forming type upon a ribbon-like blank, the combination of a device adapted to impress a character upon 20 said blank; a work-holder oscillatable a plurality of times transversely of said blank during the operation of impressing the device and having a groove arranged for the passage of said blank in which groove a portion 25 of the blank is supported during the operation of the device to form a type and means for moving said impression device and the work-holder toward each other.

67. In a machine for forming type upon a ribbon-like blank, the combination of a device adapted to impress a character upon 30 said blank; a work-holder oscillatable a plurality of times transversely of said blank during the operation of impressing the device and having a groove arranged for the passage of said blank in which groove a portion 35 of the blank is supported during the operation of the device to form a type; means for moving said impression device and the work-holder toward each other; and means for feeding the blank through the 40 groove in the work-holder.

68. In a machine for forming type upon a ribbon-like blank, the combination of a device adapted to impress a character upon 45 said blank, a work-holder oscillatable a plurality of times transversely of said blank during the operation of the impression device; and a carrier upon which the work-holder is supported and which is adapted to 50 move the work-holder toward the impression device.

69. The combination of a rotatable member; a plurality of die-carriers movable axially of said member; a plurality of dies mounted upon each of said die-carriers; and a die-carrier shifter automatically engageable 55 with any one of the die-carriers alined therewith.

70. The combination of a rotatable member; a plurality of die-carriers movable axially of said member; a plurality of dies mounted upon each of said die-carriers; a die-carrier shifter automatically engageable 60 with any one of the die-carriers alined there-

with; and means for positively locking the remaining die-carriers from axial movement when the carrier has engaged with the shifter.

71. The combination of a rotatable member; a plurality of die-carriers movable axially of said member; a plurality of dies mounted upon each of said die-carriers; a die-carrier shifter automatically engageable with any one of the die-carriers alined therewith; means for positively locking the remaining die-carriers from axial movement when the carrier has engaged with the shifter; and means for positively locking the rotatable member when a die-carrier has been shifted by the die-carrier shifter. 70

72. The combination, with a rotatable die-head, of die-bars located in said head and each provided with a cross slot; a stationary locking-plate extending into the cross slots of the die-bars; and a die-bar shifter adapted 75 to engage with an adjusted die-bar.

73. The combination of a reciprocable carrier adapted to carry a plurality of dies; and a plurality of feed elements respectively co-ordinately related to the dies and operatively 80 positioned by the carrier.

74. The combination of a plurality of reciprocatable carriers each adapted to carry a plurality of dies; and a plurality of feed elements respectively co-ordinately related to the dies and operatively positioned by the 85 several carriers.

75. In combination, with a carrier; a feed mechanism adapted to be set in an inoperative position by movement of the carrier; and an actuator for operating the mechanism. 90

76. In a typebar-machine, a feed mechanism for automatically imparting a step-by-step or intermittent movement to a continuous ribbon-like blank, in combination, with a 95 crank for manually moving the blank.

77. In a feed mechanism, the combination of gearing embodying a pawl-and-ratchet mechanism, with a carrier; a lever actuated 100 by the carrier and operating to move the pawl to an operative position; and an actuator connected to said pawl.

78. The combination of a plurality of dies reciprocatable in a plurality of paths; a member indexing said dies and reciprocatable thereby in one of the paths thereof; and a position indicator shiftable transversely of the path of the index member. 110

79. The combination of a rotatable member; a plurality of die-carriers mounted in said member; a plurality of dies mounted upon said die-carriers; an index-member indexing said dies and rotatable with the rotatable member; and a position indicator connectible with any one of the die-carriers and shiftable therewith axially of the rotatable member. 120

80. The combination of a rotatable member; a plurality of die-carriers mounted in 125

said member; a plurality of dies mounted upon said die-carriers; an index-member indexing said dies and rotatable with the rotatable member; a die-carrier shifter engageable with any of the die-carriers alined therewith; and a position indicator fixed upon the die-carrier shifter.

81. The combination of a rotatable member, a plurality of die-carriers mounted in 10 said member; a plurality of dies mounted upon said die-carriers; an index-member indexing said dies and rotatable with the rotatable member; a die-carrier shifter automatically engageable with any one of the die- 15 carriers alined therewith; and a position indicator fixed upon the die-carrier shifter.

82. In a typebar-machine, the combination, with a gage for showing the distance through which the blank has moved, of feed 20 mechanism for imparting movement to the blank.

83. In a typebar-machine, a gage for indicating the distance through which the blank has moved comprising, in combination, a 25 toothed-wheel engaging with notches in the blank; an arm or pointer adapted to move in unison with said wheel; and a movable stop extending into the path of the arm.

84. In a typebar-machine, a cutting-off 30 mechanism adapted to sever the stock of a continuous ribbon-like blank in the space between adjacent types and form a typebar it having means for engaging a space formed therefor and bringing the cutting-off mechanism to operation upon the bar at such space.

85. In a typebar machine having means for forming cutting-off indicating spaces on the stock, of a continuous ribbon-like blank, a cutting-off mechanism and means coöperative with said spaces for actuating said cutting-off mechanism at such predetermined points for forming typebars.

86. In a typebar machine having means for forming cutting-off indicating spaces on 45 the stock of a continuous ribbon-like blank, a cutting-off mechanism, and means coöperative with said spaces for automatically actuating said cutting-off mechanism at such predetermined points for forming typebars.

87. In a typebar machine having means controlled by the apparatus for forming cutting-off indicating spaces along the edge of the stock of a continuous ribbon-like blank, cutting-off mechanism, and means coöperative with said spaces for automatically actuating said cutting-off mechanism for severing said blank at such predetermined points for forming typebars.

88. In a typebar machine, the combination 60 of mechanism adapted to feed a continuous blank; a carriage reciprocatable longitudinally of said blank; a cutter mounted upon said carriage and operative to sever said blank transversely; and means operative to con-

nectibly engage said blank with the longitudinally reciprocatable member.

89. In a typebar-machine, a cutting-off mechanism adapted to automatically sever the stock of a continuous ribbon-like blank at predetermined points to form type bars, 70 said cutting off mechanism moving with the blank during the cutting off operation, in combination with means for returning the cutting-off mechanism to its original position.

90. In a typebar-machine, in combination with mechanism adapted to form types along the edge of a continuous ribbon-like blank, of a cutting-off mechanism, and means for rendering this cutting-off mechanism operative 80 to sever the stock of the blank at a point between portions of the blank provided with types.

91. In a typebar-machine, in combination with mechanism adapted to form types along 85 the edge of a continuous ribbon-like blank, of cutting-off mechanism, and means for rendering this cutting-off mechanism operative to sever the stock of the blank after the types contiguous to the point of division have been 90 formed.

92. In a typebar-machine, in combination with mechanism adapted to form types along the edge of a continuous ribbon-like blank, of cutting-off mechanism, and means for rendering this cutting-off mechanism operative 95 to automatically sever the stock of the blank after the types contiguous to the point of division have been formed.

93. In a typebar-machine, means for making a notch in the blank at a predetermined point, in combination with cutting-off mechanism rendered operative from such notch.

94. In a typebar-machine, the combination, of means for making a notch; a member adapted to engage with the notch; a releasing-lever actuated by said member upon engagement with the notch; and a cutting-off mechanism rendered operative from the movement of the releasing-lever.

95. In a typebar machine, the combination with a series of adjustable dies, means for feeding a continuous ribbon-like blank, and means for automatically severing the stock of such blank for forming a typebar after the 115 completion of the types thereon and inaugurated by an impression made by one of the said dies.

96. In a typebar machine, the combination with a series of adjustable dies, means for feeding a continuous ribbon-like blank lengthwise, means for pressing said dies and the blank against each other, and means for automatically severing the stock of such blank for forming typebars after the completion of the types upon the portion to be severed and inaugurated by an impression made by one of the dies upon said blank.

97. In a typebar-machine, the combination with a series of adjustable dies; means for feeding a continuous ribbon-like blank lengthwise; means for automatically severing the stock of such blank to form typebars; means for pressing a die and the blank against each other; and feed mechanism operative from an adjustable die.

98. In a typebar-machine, the combination with a series of adjustable dies; means for feeding a continuous ribbon-like blank lengthwise; means for automatically severing the stock of such blank to form typebars; means for pressing a die and the blank against each other; feed mechanism operative from an adjustable die; and a cutting instrument for removing excess material from the blank.

99. In a typebar-machine, the combination with a series of adjustable dies; means for feeding a continuous ribbon-like blank lengthwise; means for automatically severing the stock of such blank to form typebars; means for pressing the die and the blank against each other; feed mechanism operative from an adjustable die; a cutting instrument for removing excess material from the blank; and means for indicating the amount of feed movement of the blank.

100. In a typebar-machine, the combination with a series of adjustable dies; means for feeding a continuous ribbon-like blank lengthwise; means for automatically severing the stock of such blank to form typebars; means for pressing a die and the blank against each other; feed mechanism operative from an adjustable die; a cutting instrument for removing excess material from the blank; means for indicating the amount of feed movement of the blank; and means for notching the blank at predetermined points.

101. In a typebar-machine, the combination with a series of adjustable dies; means for feeding a continuous ribbon-like blank lengthwise; means for automatically severing the stock of such blank to form typebars; means for pressing a die and the blank against each other; feed mechanism operative from an adjustable die; a cutting instrument for removing excess material from the blank; means for indicating the amount of feed movement of the blank; means for notching the blank at predetermined points; and a member for engaging with the notch and rendering the cutting-off mechanism operative.

102. In a typebar-machine, the combination with a series of adjustable dies; means for feeding a continuous ribbon-like blank lengthwise; means for automatically severing the stock of such blank to form typebars embodying a saw adapted to move transversely across the blank; means for pressing a die and the blank against each other; feed mechanism operative from an adjustable die;

a cutting instrument for removing excess material from the blank; means for indicating the amount of feed movement of the blank; means for notching the blank at predetermined points; and a member for engaging with the notch and rendering the cutting-off mechanism operative.

103. In a typebar-machine, the combination with a series of adjustable dies; means for feeding a continuous ribbon-like blank lengthwise; means moving in unison with the feed movement of the blank for automatically severing the stock of such blank to form typebars embodying a saw adapted to move transversely across the blank; means for pressing a die and the blank against each other; feed mechanism operative from an adjustable die; a cutting instrument for removing excess material from the blank; means for indicating the amount of feed movement of the blank; means for notching the blank at predetermined points; and a member for engaging with the notch and rendering the cutting-off mechanism operative.

104. In a typebar-machine, the combination with a series of adjustable dies; means for feeding a continuous ribbon-like blank lengthwise; means for automatically severing the stock of such blank to form typebars; means for pressing a die and the blank against each other; feed mechanism operative from an adjustable die; a cutting instrument for removing excess material from the blank; means for indicating the amount of feed movement of the blank; means for notching the blank at predetermined points; a member for engaging with the notch and rendering the cutting-off mechanism operative; and a fixed stop for causing the release of the member and permitting the return of the cutting-off mechanism to its original position.

105. In a typebar-machine, the combination with a series of adjustable dies; means for feeding a continuous ribbon-like blank lengthwise; means for automatically severing the stock of such blank to form typebars; means for pressing a die and the blank against each other; feed mechanism operative from an adjustable die; a cutting instrument for removing excess material from the blank; means for indicating the amount of feed movement of the blank; means for notching the blank at predetermined points; a member for engaging with the notch and rendering the cutting-off mechanism operative; a fixed stop for causing the release of the member and permitting the return of the cutting-off mechanism to its original position; and a main driving-shaft.

106. In a typebar-machine, the combination with a series of adjustable dies; means for feeding a continuous ribbon-like blank lengthwise; means for automatically severing

the stock of such blank to form typebars; means for pressing a die and the blank against each other; feed mechanism operative from an adjustable die; a cutting instrument for removing excess material from the blank; means for indicating the amount of feed movement of the blank; means for notching the blank at predetermined points; a member for engaging with the notch and rendering the cutting-off mechanism operative; a fixed stop for causing the release of the member and permitting the return of the cutting-off mechanism to its original position; a main driving-shaft; and a key for rendering said main shaft operative.

107. In a typebar-machine, in combination with dies operating to produce types by a rolling movement; means for making a notch in the blank at a predetermined point; and cutting-off mechanism rendered operative from such notch.

108. In a typebar-machine, in combination with dies operating to produce types by a rolling movement; means for making a notch; a member adapted to engage with the notch; a releasing-lever actuated by said member upon engagement with the notch; and a cutting-off mechanism rendered operative from the movement of the releasing lever.

109. In a typebar-machine, in combination with dies operating to produce types by a rolling movement; a series of adjustable dies; means for feeding a continuous ribbon-like blank; and means for automatically severing the stock of such blank to form typebars.

110. In a typebar-machine, in combination with dies operating to produce types by a rolling movement; a series of adjustable dies; means for feeding a continuous ribbon-like blank lengthwise; means for automatically severing the stock of such blank to form typebars; and means for pressing a die and the blank against each other.

111. In a typebar-machine, in combination with dies operating to produce types by a rolling movement; a series of adjustable dies; means for feeding a continuous ribbon-like blank lengthwise; means for automatically severing the stock of such blank to form typebars; means for pressing a die and the blank against each other; and feed mechanism operative from an adjustable die.

112. In a typebar-machine, in combination with dies operating to produce types by a rolling movement; a series of adjustable dies; means for feeding a continuous ribbon-like blank lengthwise; means for automatically severing the stock of such blank to form typebars; means for pressing a die and the blank against each other; feed mechanism operative from an adjustable die; and a cutting instrument for removing excess material from the blank.

113. In a typebar-machine, in combination with dies operating to produce types by a rolling movement; a series of adjustable dies; means for feeding a continuous ribbon-like blank lengthwise; means for automatically severing the stock of such blank to form typebars; means for pressing a die and the blank against each other; feed mechanism operative from an adjustable die; a cutting instrument for removing excess material from the blank; and means for indicating the amount of feed movement of the blank.

114. In a typebar-machine, in combination with dies operating to produce types by a rolling movement; a series of adjustable dies; means for feeding a continuous ribbon-like blank lengthwise; means for automatically severing the stock of such blank to form typebars; means for pressing a die and the blank against each other; feed mechanism operative from an adjustable die; a cutting instrument for removing excess material from the blank; means for indicating the amount of feed movement of the blank; and means for notching the blank at predetermined points.

115. In a typebar-machine, in combination with dies operating to produce types by a rolling movement, a series of adjustable dies; means for feeding a continuous ribbon-like blank lengthwise; means for automatically severing the stock of such blank to form typebars; means for pressing a die and the blank against each other; feed mechanism operative from an adjustable die; a cutting instrument for removing excess material from the blank; means for indicating the amount of feed movement of the blank; means for notching the blank at predetermined points; and a member for engaging with the notch and rendering the cutting-off mechanism operative.

116. In a typebar-machine, in combination with dies operating to produce types by a rolling movement; a series of adjustable dies; means for feeding a continuous ribbon-like blank lengthwise; means for automatically severing the stock of such blank to form typebars embodying a saw adapted to move transversely across the blank; means for pressing a die and the blank against each other; feed mechanism operative from an adjustable die; a cutting instrument for removing excess material from the blank; means for indicating the amount of feed movement of the blank; means for notching the blank at predetermined points; and a member for engaging with the notch and rendering the cutting-off mechanism operative.

117. In a typebar-machine, in combination with dies operating to produce types by a rolling movement; a series of adjustable dies; means for feeding a continuous ribbon-like blank lengthwise; means moving in uni-

- son with the feed movement of the blank for automatically severing the stock of such blank to form typebars embodying a saw adapted to move transversely across the
- 5 blank; means for pressing a die and the blank against each other; feed mechanism operative from an adjustable die; a cutting instrument for removing excess material from the blank; means for indicating the amount of
- 10 feed movement of the blank; means for notching the blank at predetermined points; and a member for engaging with the notch and rendering the cutting-off mechanism operative.
- 15 118. In a typebar-machine, in combination with dies operating to produce types by a rolling movement; a series of adjustable dies; means for feeding a continuous ribbon-like blank lengthwise; means for automatically severing the stock of such blank to form typebars; means for pressing a die and the blank against each other; feed mechanism operative from an adjustable die; a cutting instrument for removing excess material
- 20 from the blank; means for indicating the amount of feed movement of the blank; means for notching the blank at predetermined points; a member for engaging with the notch and rendering the cutting-off mechanism operative; 85 a fixed stop for causing the release of the member and permitting the return of the cutting-off mechanism to its original position; and an oscillator for imparting an oscillatory movement to a portion of the blank. 90
119. In a typebar-machine, in combination with dies operating to produce types by a rolling movement; a series of adjustable dies; means for feeding a continuous ribbon-like blank lengthwise; means for automatically severing the stock of such blank to form typebars; means for pressing a die and the blank against each other; feed mechanism operative from an adjustable die; a cutting instrument for removing excess material from the blank; means for notching the blank
- 25 at predetermined points; a member for engaging with the notch and rendering the cutting-off mechanism operative; a fixed stop for causing the release of the member and permitting the return of the cutting-off mechanism to its original position; and a main driving-shaft. 105
120. In a typebar-machine, in combination with dies operating to produce types by a rolling movement; a series of adjustable dies; means for feeding a continuous ribbon-like blank lengthwise; means for automatically severing the stock of such blank to form typebars; means for pressing a die and the blank against each other; feed mechanism operative from an adjustable die; a cutting instrument for removing excess material from the blank; means for indicating the amount of feed movement of the blank; means for notching the blank at predetermined points; 115
- 30 a member for engaging with the notch and rendering the cutting-off mechanism operative; a fixed stop for causing the release of the member and permitting the return of the cutting-off mechanism to its original position; a main driving-shaft; and an oscillator for imparting an oscillatory movement to a portion of the blank. 120
123. In a typebar-machine, the combination with a series of adjustable dies; means for feeding a continuous ribbon-like blank lengthwise; means for automatically severing the stock of such blanks to form typebars; means for pressing a die and the blank against each other; feed mechanism operative from an adjustable die; a cutting instrument for removing excess material from the blank; means for indicating the amount of feed movement of the blank; means for notching the blank at predetermined points; a member for engaging with the notch and rendering the cutting-off mechanism operative; a fixed stop for causing the release of the member and permitting the return of the cutting-off mechanism to its original position; a main driving-shaft; a key for render- 125
- a member for engaging with the notch and 65 rendering the cutting-off mechanism operative; a fixed stop for causing the release of the member and permitting the return of the cutting-off mechanism to its original position; a main driving-shaft; and a key for rendering 70 said main shaft operative.
121. In a typebar-machine, the combination with a series of adjustable dies; means for feeding a continuous ribbon-like blank lengthwise; means for automatically severing 75 the stock of such blank to form typebars; means for pressing a die and the blank against each other; feed mechanism operative from an adjustable die; a cutting instrument for removing excess material from the blank; means for indicating the amount of feed movement of the blank; means for notching the blank at predetermined points; a member for engaging with the notch and rendering the cutting-off mechanism operative; 80 a fixed stop for causing the release of the member and permitting the return of the cutting-off mechanism to its original position; and an oscillator for imparting an oscillatory movement to a portion of the blank. 85
122. In a typebar-machine, the combination with a series of adjustable dies; means for feeding a continuous ribbon-like blank lengthwise; means for automatically severing the stock of such blank to form typebars; 95 means for pressing a die and the blank against each other; feed mechanism operative from an adjustable die; a cutting instrument for removing excess material from the blank; means for indicating the amount of feed movement of the blank; means for notching the blank at predetermined points; a member for engaging with the notch and rendering the cutting-off mechanism operative; a fixed stop for causing the release of the member and permitting the return of the cutting-off mechanism to its original position; a main driving-shaft; and an oscillator for imparting an oscillatory movement to a portion of the blank. 100
124. In a typebar-machine, the combination with a series of adjustable dies; means for feeding a continuous ribbon-like blank lengthwise; means for automatically severing the stock of such blank to form typebars; means for pressing a die and the blank against each other; feed mechanism operative from an adjustable die; a cutting instrument for removing excess material from the blank; means for indicating the amount of feed movement of the blank; means for notching the blank at predetermined points; a member for engaging with the notch and rendering the cutting-off mechanism operative; a fixed stop for causing the release of the member and permitting the return of the cutting-off mechanism to its original position; a main driving-shaft; and an oscillator for imparting an oscillatory movement to a portion of the blank. 110

ing said main shaft operative; and an oscillator for imparting an oscillatory movement to a portion of the blank.

124. In a typebar-machine, the combination with a series of adjustable dies; means for feeding a continuous ribbon-like blank lengthwise; means for automatically severing the stock of such blank to form typebars; means for pressing a die and the blank 10 against each other; feed mechanism operative from an adjustable die; a cutting instrument for removing excess material from the blank; means for indicating the amount of feed movement of the blank; means for 15 notching the blank at predetermined points; a member for engaging with the notch and rendering the cutting-off mechanism operative; a fixed stop for causing the release of the member and permitting the return of the 20 cutting-off mechanism to its original position; and an oscillator adapted to impart a variable oscillatory motion to a portion of the blank.

125. In a typebar-machine, the combination with a series of adjustable dies; means for feeding a continuous ribbon-like blank lengthwise; means for automatically severing the stock of such blank to form typebars; means for pressing a die and the blank 30 against each other; feed mechanism operative from an adjustable die; a cutting instrument for removing excess material from the blank; means for indicating the amount of feed movement of the blank; means for 35 notching the blank at predetermined points; a member for engaging with the notch and rendering the cutting-off mechanism operative; a fixed stop for causing the release of the member and permitting the return of the 40 cutting-off mechanism to its original position; a main driving-shaft; and an oscillator adapted to impart a variable oscillatory motion to a portion of the blank.

126. In a typographic machine, the combination of a rotatable member; a plurality of axially movable die-carriers mounted thereon; and a member locking said rotatable member.

127. In a typographic machine, the combination of a rotatable member; a plurality of die-carriers mounted thereon; a work-holder adapted to hold a bar or strip of material, and means for reciprocating the die-carriers toward and from the work-holder.

128. In a machine for making a line of type, the combination with type making mechanism adapted to make type one after another along the edge of a ribbon-like blank, of feed mechanism adapted to feed the blank 60 in consonance with the line space values of the successive types, and a blank severing mechanism for automatically and successively cutting off typebar lengths from the type-provided portions of said blank.

129. In a machine for making a line of

type, the combination with type making mechanism adapted to make type one after another along the edge of a ribbon-like blank, of feed mechanism adapted to feed the blank 70 in consonance with the line space values of the successive types, a supplemental feed mechanism for manually feeding the blank, and a blank severing mechanism for automatically and successively cutting off typebar lengths from the type-provided portions 75 of said blank.

130. In a machine for making a line of type, the combination with type making mechanism comprising means for imparting a to and fro movement to one of the type 80 making members at each type making operation at successive points along the edge of a ribbon like blank, of feed mechanism adapted to feed the blank in consonance with the line space values of the successive types, and 85 a blank severing mechanism for automatically and successively cutting off typebar lengths from the type-provided portions of said blank.

131. In a machine for making a line of type, the combination with type making mechanism comprising means for imparting a to and fro movement, directed transversely of the blank, to one of the type making members at each type making operation at successive points along the edge of a ribbon-like 95 blank, of a feed mechanism adapted to feed the blank in consonance with the line space values of the successive types, and a blank severing mechanism for automatically and 100 successively cutting off typebar lengths from the type-provided portions of said blank.

132. The combination with a plurality of adjustable type dies, of feed mechanism for imparting lengthwise movement to a continuous blank, means for forcing a die and a blank against each other, and a stock-removing cutter for automatically severing, under the control of the blank, a typebar therefrom and movable with the blank in its 110 lengthwise movement.

133. The combination with a type die, of feed mechanism for imparting lengthwise movement to a continuous blank, means for forcing a die and a blank against each other, and a stock removing cutter automatically 115 controlled by the stock for severing a completed typebar therefrom and movable with the blank in its lengthwise movement.

134. In a typebar-machine, in combination with dies operating to produce types, of means for making a notch in the blank at a predetermined point, and cutting-off mechanism rendered operative from such notch.

135. In a typebar-machine, in combination with dies operating to produce types, of means for making a notch, a member adapted to engage with the notch, a releasing-lever actuated by said member upon engagement with the notch, and a cutting-off mechanism 130

rendered operative from the movement of the releasing lever.

136. The combination with a die, of a work holder provided with a bearing face, a carrier provided with a thrust receiving roller for the work holder, means for guiding the carrier for movement in a straight line toward and from the working position of the die, means for reciprocating the carrier, members oscillatory about a fixed axis and provided with slides in which said work holder is mounted for reciprocation, means operatively connected with the carrier reciprocating means for oscillating the work holder.

137. The combination with a die, of a carrier, widely spaced apart guide blocks upon the carrier for a ribbon like blank, said blocks being situated upon the respective sides of the working position of the die, means for advancing the carrier toward the working position of the die, a work holder, brackets located between said guide blocks, members pivoted to the brackets and provided with ways for the work holder, a roller on the carrier for engaging a bearing face on the holder, and means for oscillating the said holder.

tween said guide blocks, members pivoted to the brackets and provided with ways for the work holder, a roller on the carrier for engaging a bearing face on the holder, and means for oscillating the said holder with gradually decreasing amplitude.

138. The combination with a die, of a carrier, widely spaced apart guide blocks upon the carrier for a ribbon like blank, said blocks being situated upon the respective sides of the working position of the die, means for advancing the carrier toward the working position of the die, a work holder, brackets located between said guide blocks, members pivoted to the brackets and provided with ways for the work holder, a roller on the carrier for engaging a bearing face on the holder, and means for oscillating the said holder.
